US0D1107701S

(12) **United States Design Patent** (10) **Patent No.:** **US D1,107,701 S**
(45) **Date of Patent:** **** Dec. 30, 2025**

(54) **DISPLAY**

(71) Applicant: **Panasonic Intellectual Property Management Co., Ltd.**, Kadoma (JP)

(72) Inventor: **Yuki Odoriba**, Osaka (JP)

(73) Assignee: **PANASONIC INTELLECTUAL PROPERTY MANAGEMENT CO., LTD.**, Osaka (JP)

(**) Term: **15 Years**

(21) Appl. No.: **29/943,970**

(22) Filed: **May 24, 2024**

(51) LOC (15) Cl. **14-02**

(52) U.S. Cl.

USPC **D14/371**; D16/220

(58) **Field of Classification Search**

USPC D14/336, 341, 371, 376, 377, 126, 375, D14/125, 129, 374; D16/218-220

CPC G06F 1/1601; G06F 1/1605; G06F 1/1626; G06F 1/1637; G06F 1/1652; H04N 5/64

See application file for complete search history.

(57) **CLAIM**

The ornamental design for a display, as shown and described.

DESCRIPTION

FIG. 1 is a first perspective view of a display showing my new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a third perspective view thereof in a first flexed state; and,

FIG. 10 is a fourth perspective view thereof in a second flexed state.

The broken lines in the drawings illustrate portions of the display that form no part of the claimed design.

1 Claim, 10 Drawing Sheets
